US00D804410S

(12) **United States Design Patent** (10) Patent No.: **US D804,410 S**
(45) Date of Patent: ** Dec. 5, 2017

(54) **CHARGER**

(71) Applicant: **eMoMo Technology Co., Ltd.**,
Shenzhen (CN)

(72) Inventors: **Wenji Tang**, Shenzhen (CN); **Huiyao An**, Shenzhen (CN); **Rui Zou**, Shenzhen (CN); **Keyun Zhang**, Jinshi (CN); **Zhigang Wang**, Qiyang (CN); **Yushu Zhao**, Shenzhen (CN)

(73) Assignee: **EMOMO TECHNOLOGY CO., LTD.**,
Shenzhen (CN)

(**) Term: **15 Years**

(21) Appl. No.: **29/568,671**

(22) Filed: **Jun. 20, 2016**

Related U.S. Application Data

(63) Continuation-in-part of application No. 29/553,760, filed on Feb. 4, 2016.

(57) **CLAIM**

The ornamental design for a charger, as shown and described.

DESCRIPTION

FIG. 1 is a front view of a charger showing our new design;
FIG. 2 is a top plan view thereof;
FIG. 3 is a bottom plan view thereof;
FIG. 4 is a rear view thereof;
FIG. 5 is a left side view thereof;
FIG. 6 is a right side view thereof; and,
FIG. 7 is a front perspective view thereof.
The broken lines in the drawings are for the purpose of illustrating portions of the charger that form no part of the claimed design.

1 Claim, 7 Drawing Sheets
